United States Patent Office.

JAMES T. SMITH AND JOHN WALTER, OF BALTIMORE, MARYLAND.

Letters Patent No. 70,757, dated November 12, 1867.

IMPROVEMENT IN STEAM-GENERATORS.

The Schedule referred to in these Letters Patent and making part of the same.

TO ALL WHOM IT MAY CONCERN:

Be it known that we, JAMES T. SMITH and JOHN WALTER, of Baltimore, in the county of Baltimore, and State of Maryland, have invented certain new and useful Improvements in Steam-Boilers; and we do hereby declare that the following is a full, clear, and exact description thereof, reference being had to the accompanying drawings, and to the letters of reference marked thereon, which form a part of this specification. In the annexed drawings, which make a part of this specification—

Figure 1 represents an end view of our boilers when in position.

Figure 2 is a side elevation of the same.

Figure 3 represents a vertical section of a single boiler cast with its water-pipe connection.

Our invention consists of a series of boilers, A, connected in the manner hereinafter described. Each boiler A, in the outside series, will be cast with wings b attached; the said wings being five-eighths of an inch, more or less, in thickness. The wings b are cast with a hole through them to receive a rod or bolt, (see fig. 3;) the said hole being of sufficient capacity to contain a quantity of water, which can pass from boiler A in wings b through an orifice marked t in fig. 3. When the whole series of boilers is united and arranged as seen in fig. 2, and the wings being made to fit with a close joint, a wall of iron will be thus interposed between the furnace and the wood-work of the boat or building in which our boilers may be used.

In order to join the several boilers in each vertical series, the two boiler-necks to be thus connected will have their bore enlarged to the distance of several inches, having a square shoulder at bottom to receive a metal band, e, (see fig. 3;) one-half of said band entering the neck of each of the boilers, and forming a water-tight connection. E represents the mud or feed pipe, of which there are two, one supporting each of the outside tier of boilers. The pipes E are tubular, with a flange at each end, and having a cap screwed on each flange. On the outside of sills E, two tubes g are inserted; the bore of said tubes communicating with the bore in sill E. Through one of these tubes the water is received to supply the boilers, the other is used for blowing out the boilers. Extending the whole length of sill E, and cast solid with it, is the elevation F, which is made with a plane surface, with enlargements C at stated distances apart. Into said enlargements the lower tier of boilers are made to fit. Through enlargements C, which are tubular, the water is conveyed into the boilers A. H represents a pipe for containing water, and is connected with the upper tier of boilers by three or more short pipes. The ends of pipe H are secured by caps similar to those used for sill E.

It will be remarked that there are five tier of boilers; the centre tier having only two boilers in each series, and the others three in each series. This number can be varied when required. On the top of the centre tier are placed the goose-neck branch pipes L, through which the steam will ascend into a drum above, and thence conveyed in the usual manner to the cylinder. As our boilers are all connected together, that is to say, the boilers of each tier being connected by two pipes n n with the corresponding boilers in the tier next to it, the water must pass equally through the whole series. It will be seen also that the boilers are so arranged above the furnace that the heat can pass freely between the several tiers, and thus act at once upon the greatest possible surface, and generate steam the more rapidly.

In order to clean out the boilers with the least possible labor, all the upper boilers have a cap, s, bolted on them at top; the said bolts extending down to the feed pipe F. The said caps can be easily taken off and any obstructions in the boilers removed. In addition to the cap s on the top of the outside tier of boilers, those on the three inner tiers are also furnished with similar caps at bottom, which can be easily removed, and the boilers thoroughly cleansed from end to end. That the volume of heated water may be as great as possible, to supply the boilers, each boiler has two tubes m cast in connection with it, which said tubes communicate with the boiler through the orifice t, as seen in fig. 3. Through these tubes m the bolts pass that confine the boilers together. The tubes m are jointed in a manner similar to the boilers, as already described; or, if preferred, the hole at the upper end of one tube m may be chamfered, and the adjoining tube bevelled to fit it.

The advantage we claim for our construction of boilers is the facility with which they can be freed from incrustations, by having the bolts that unite the boilers together pass through the tubes m, instead of through the boilers themselves. We claim also that we provide a great safeguard against fire by the use of wings b, whereby a continuous iron wall is formed between the furnace and the adjacent wood-work and coal-bunks.

We are aware of the existence of the boiler patented by Joseph Harrison, Jr., August 8, 1865; we therefore disclaim all contained in said patent.

Having thus described our invention, what we claim, and desire to secure by Letters Patent, is—

1. The interior series of boilers A, connected with tubes *n*, and supplied with caps *s* at each end, the whole constructed and operating substantially as set forth.

2. The mud-sills E, pipes H, in combination with the outside tier of boilers A, operating as and for the purpose substantially as herein described.

3. The goose-neck branch pipes L, in combination with the central tier of boilers A, constructed as and for the purpose substantially as set forth.

In testimony that we claim the foregoing as our own, we have affixed our signatures in presence of two witnesses.

JAS. T. SMITH,
JOHN WALTER.
